United States Patent Office

Des. 198,506
Patented June 23, 1964

198,506

SPOON OR SIMILAR ARTICLE

Magnus Stephensen, Copenhagen, Denmark, assignor to
Georg Jensens Solvsmedie A/S, Copenhagen, Denmark

Filed Dec. 7, 1961, Ser. No. 67,828

Claims priority, application Denmark June 9, 1961

Term of patent 14 years

(Cl. D54—12)

FIGURE 1 is a front elevational view of a spoon or similar article showing my new design;

FIGURE 2 is a right side elevational view thereof;

FIGURE 3 is a rear elevational view thereof;

FIGURE 4 is a left side elevational view thereof;

FIGURE 5 is an enlarged fragmentary sectional view taken along line 5-5 of FIGURE 1, and

FIGURE 6 is an enlarged sectional view taken along line 6-6 of FIGURE 1.

The back of the handle which is plain and unornamented complements the concave curvature of the front of the handle.

I claim:

The ornamental design for a spoon or similar article, as shown and described.
